EDWIN E. KLINE, WILLIAM R. WRIGHT, AND FRED N. HUNT, ALL OF CROMWELL,
INDIANA.

COMBINATION TOOL.

1,421,220.

Specification of Letters Patent. Patented June 27, 1922.

Application filed April 10, 1920. Serial No. 372,744.

To all whom it may concern:

Be it known that I, ALBERT J. HART, a citizen of the United States, and resident of Cromwell, in the county of Noble and State 5 of Indiana, have invented a new and Improved Combination Tool, of which the following is a full, clear, and exact description.

This invention relates to tools and more 10 particularly to a combination tool.

Many combination tools have been constructed and designed in order to provide a single tool for various purposes to take place of a multiplicity; but it has been found that 15 in the majority of cases, it is necessary to remove a part of the tool in order to adapt the same for various uses, which has been found objectionable.

One of the principal objects of the present 20 invention is to provide a simple, compact, and durable tool which is designed to perform the work of a plurality of independent tools without the necessity of removing a single element of the combination.

Another object of the invention is to provide a tool which is capable of functioning 25 as a wrench, pliers, a hammer, a nail-puller, a vise, a wire cutter, a clamp, or a nut-cracker.

With these and other objects and advantages in view, some of which will be more readily apparent hereafter, reference is made to the following description, claims, and accompanying drawings in which—

Figure 1 is a side elevation view of the tool illustrating in full and dotted lines several positions of the parts thereof;

Fig. 2 is a vertical sectional view therethrough;

Fig. 3 is a horizontal sectional view on the line 3—3 of Fig. 1; and

Fig. 4 is a fragmentary side view of the tool illustrating one of the uses of the same.

Referring to the drawings by characters 45 of reference which denote like parts throughout the several views thereof, 10 designates a shank which is preferably of rectangular formation in cross-section and is provided with worm threads 11 on the opposite edges 50 thereof from substantially the center of its length to one extremity thereof. The opposite extremity of said shank is provided with a head 12 which may be cast thereon or otherwise secured thereto. The head 12 55 includes laterally projecting portions 13 and

14, the outer side face of the former constituting a hammer head and the inner underside of the latter a fixed jaw having teeth 15 formed thereon. The outer end of the head 12 is formed to provide a curved 60 cam surface 16 which merges respectively at its opposite ends into the hammer head and the outer extremity of the fixed jaw, and a portion of the under edge of the laterally projecting portion constituting the hammer 65 head 13 is sharpened as at 17. A traveler 18 in the nature of a rectangular sleeve having alined transverse openings 19 for the reception of a nut 20, is slidable on the threaded portion of the shank, movements of the 70 same being effected by means of the engagement of the threaded bore of the nut with the worm threads 11. A transverse pin 21 passed through the outer threaded extremity of the shank 10 serves to limit the outward 75 movement of the traveler and prevent its entire removal from the shank. A slideable member movable on the shank between the traveler 18 and the head 12 is provided and includes the longitudinal bars 22 and 23 disposed at the opposite side edges of the shank 10 and connected by the side plates 24 by means of rivets 25. The upper extremity of the bar 22 is enlarged to provide a movable 80 jaw 26 having teeth 27 formed on its upper 85 surface. The upper extremity of the bar 23 is extended above the side plates 24 and is sharpened as at 28 whereby to co-act with the sharpened edge 17 to constitute a wire cutter. The lower extremity of each bar 22 90 and 23 is extended below the lower end of the side plates 24 and is apertured for the reception of the rivets 29 which constitute pivots for the lever arms 30. A link 31 is pivoted at one extremity as at 32 to each lever arm 30 and at its opposite extremity as at 33 to the traveler whereby to constitute substantially a toggle connection between the traveler and the movable member. The extremity of each link adjacent its pivot 33 95 is provided with an outwardly disposed lug 34. The outer free extremity 35 of each lever arm 30 constitutes a handle which is preferably of semicircular formation in cross-section to provide a rounded gripping 100 surface for the hand, and said handles also serve, when closed, as a partial housing to prevent the contact of the operator's hand with the nut 20.

In use of the device it will be understood, 110

that upon turning the nut 20 the traveler 18 will be advanced toward or away from the head 12, said nut serving also as a means for retaining the traveler in its adjusted 5 positions. The levers 30 may then be employed as a means for effecting relative adjustments of the movable member with respect to the head 12 and the traveler 18 whereby to advance the movable jaw 26 toward or away from the fixed jaw 14. In use of the device as an ordinary wrench the levers 30 are closed as illustrated in full lines in Fig. 1 of the drawing, and the nut 20 is used in the usual manner to advance the 10 movable jaw 26 toward the fixed jaw 14. In this instance the movable member, the traveler, and the toggle connection merely function as a single traveler member. In use of the device as a wire cutter the traveler 18, 15 with the levers 30 in closed position, is advanced together with the movable member toward the head 12 until the edges 17 and 28 contact; the levers are then opened and the wire to be cut inserted between the edges 17 and 28 and the levers are then brought together to advance the edges 17 and 28 toward each other for severing the wire. In use of the device as a pipe wrench the jaws 14 and 26 are adjusted apart to provide a space 20 slightly less than the diameter of the pipe and the handles are opened to permit of the insertion of the pipe therebetween; the handles are then closed until the jaws grip the pipe and then loosened to permit retrograde movement of the wrench and allow the jaws to obtain a new grip. In use of the device as a clamp the movable jaw is advanced toward the fixed jaw to grip the object with the levers 30 slightly opened; the levers 30 are then moved toward each other until the inner sides of the same contact with the lugs 34. This operation will dispose the pivots 32 inside of a dead-center line extending between the pivots 29 and 33, thereby locking 35 the jaws in clamping relation with respect to the object. In use of the device as a nail-puller as illustrated in Fig. 4 the teeth of the jaws 14 and 26 are designed to engage the head of the nail adjacent their outer extremities under the action of the compression of the handles 35, and using the curved surface 16 as a fulcrum the handle of the wrench is used as a lever to extract the nail. In use of the device as a hammer, it is obvious 40 that the handles 35 are gripped in closed position and the head 13 used as the striking surface.

As illustrated in Fig. 1 the rearwardly extended terminal portions of the bars 22 and 60 23 are directly connected to the handles by

means of rivets 29 so that pressure on the handles is transmitted directly through the bars to the work-engaging devices. This greatly lessens the strain on the various parts of the device and is a feature not shown 65 in the art.

While there has been illustrated and described a single and preferred embodiment of the invention, no limitation is made to the precise details of construction, and it is understood that variations and modifications which fall within the scope of the appended claims may be resorted to when found expedient.

Having thus described my invention, I 75 claim as new and desire to secure by Letters Patent:—

1. A tool comprising a shank having a fixed jaw, a second jaw slidable on said shank and having rearwardly projecting extensions at opposite edges of said shank, levers arranged on opposite edges of said shank and pivoted to the extensions of said sliding jaw, a traveler on said shank and having ears, and links pivoted to said ears and said levers, said levers being formed with channels receiving said links and ears, whereby the hand of the operator is protected from engagement with the links and ears.

2. The construction set forth in claim 1, 90 and a nut associated with the traveler and threaded on said shank.

3. A tool comprising a shank having a fixed head, a member slidable on said shank and consisting of oppositely arranged side plates and separately formed bars arranged at the edges of the shank between the side plates, means passing through the side plates and the bars for connecting the same, the forward portions of said bars being extended beyond said side plates and formed with work-engaging means cooperating with said head, and an adjusting device for said sliding member.

4. A tool comprising a shank having a 105 fixed head, a member slidable on said shank and comprising oppositely arranged side plates and separately formed bars arranged at the edges of the shank between the side plates, means passing through the side plates 110 and the bars for connecting the same, the forward portions of said bars being extended beyond said side plates and formed with work-engaging means cooperating with said head, the rear portions of said bars terminating rearwardly of said side plates, and means connected directly to the extended rear terminal portions of said bars for positioning said member.

ALBERT JASPER HART.
